US00D849754S

(12) **United States Design Patent** (10) **Patent No.:** **US D849,754 S**
(45) **Date of Patent:** **** May 28, 2019**

(54) **DISPLAY SCREEN OR PORTION THEREOF
WITH GRAPHICAL USER INTERFACE**

(71) Applicant: **KING.COM LIMITED**, St. Julian's (MT)

(72) Inventors: **Rick Thompson**, St. Julian's (MT);
Sean Hayden, St. Julian's (MT);
Gabriel Loques, St. Julian's (MT);
Eugene Teh, St. Julian's (MT); **Hollie Taylor**, St. Julian's (MT); **Anthony Simpson**, St. Julian's (MT)

(73) Assignee: **KING.COM LTD.**, St. Julians (MT)

(**) Term: **15 Years**

(21) Appl. No.: **29/596,147**

(22) Filed: **Mar. 6, 2017**

Related U.S. Application Data

(63) Continuation of application No. 29/484,617, filed on Mar. 11, 2014, now Pat. No. Des. 780,776.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing our new design.

The broken lines around the FIGURE showing a display screen or a portion thereof form no part of the claimed design.

1 Claim, 1 Drawing Sheet
